E. FERRISS.
MACHINE FOR REDUCING BRASSES OF JOURNALS.

No. 483,956.

Patented Oct. 4, 1892.

UNITED STATES PATENT OFFICE.

EDWARD FERRISS, OF ALTA, CALIFORNIA, ASSIGNOR OF ONE-HALF TO
NELSON A. JONES, OF SAME PLACE.

MACHINE FOR REDUCING BRASSES OF JOURNALS.

SPECIFICATION forming part of Letters Patent No. 483,956, dated October 4, 1892.

Application filed October 14, 1891. Serial No. 408,729. (No model.)

To all whom it may concern:

Be it known that I, EDWARD FERRISS, a citizen of the United States, residing at Alta, in the county of Placer and State of California, 5 have invented a new and useful Machine for Reducing Brasses of Journal - Bearings, of which the following is a specification.

The object of my invention is to produce a machine for reducing the brasses of journal- 10 bearings; and it consists in the construction and combination of parts, as hereinafter described, by which I have produced a simple, portable, and handy machine for finishing the faces of journal-brasses more rapidly and 15 more perfectly than has heretofore been possible under the ordinary methods of finishing by hand or in a lathe.

The following description explains the manner in which I proceed to construct my said 20 machine, the accompanying drawings being referred to therein by letters.

Figure 1 of the drawings is an end elevation of the machine. Fig. 2 is a side elevation with a portion of the bed broken away. 25 Fig. 3 is a side view of the cutters, partly in section.

A is the bed of the machine, having a post A' in the center of one end and a cross-head B at the opposite end, or what I have termed 30 the "head," of the machine. The sides of this bed are raised above the bottom and are finished true and smooth along the top edges to form wings for the moving planer, and these sides at the head of the machine extend above 35 the ways and form posts to carry the cross-head B. This part is fixed on the posts by top-bolts, as shown in Fig. 1, and is elevated sufficiently above the ways to let the planer pass under it.

40 B' is the standard in the center of the cross-head, having a square eye or opening B² to take a sliding arm C, on the end of which is a threaded socket C' for a clamping-screw D, with a flat bottom end and a hand-wheel on 45 top. The office of this screw is to hold the brass down against the planer, and it is set in position by shifting the arm c in the post B'.

E is a sliding plate fitted to slide on the ways at the sides of the bed and between the 50 uprights at the head of the machine on which the cross-head is fixed.

Two plates F F^x, each with a beveled cutting-edge f and about one-half the length of the slide, but of corresponding width, are fixed on the top face of the slide by screws f² 55 f³, which set through the slide from beneath, in order to leave the top surface smooth, and g is a shim or thin metal plate inserted between the plate F and the carrier E, to raise the beveled cutting-edge the desired amount 60 above the face of the other plate F^x to produce the cut. The depth of cut or thickness of the shaving that the cutter will make in moving under the brass is varied by changing the shim g for another of different thickness. This is a simple and effective mode of regulating the depth of cut. It will be noticed that while both planing-irons have beveled cutting-edges the planer F, or the one 65 nearest the post A', is the cutter, and the other iron holds and presents the brass in a horizontal or level position to the cutter and that the end of the plate F^x, which is set toward the beveled edge of the plate F, may be square, as well as beveled, so far as the cutting-operation is concerned. The object of 70 constructing the two plates F F^x of the same size and with cutting-edge on each is to make them interchangeable, so that when the plate F is worn dull or the edge becomes broken 75 the plate F^x may be turned and set in working position, while the plate F is substituted in its place.

I is a long screw-rod with a capstan-head and hand-bar J working in a screw-threaded 85 bearing in the post A' in line with the end of the sliding planer and having its point set against a clip or loose block h, that takes the thrust of the screw. This piece has turned-over ends to set over both plates E F and is 90 used to distribute the pressure of the screw against the ends of both plates.

In the operation of my improved machine the cutter-plate is run back to the post A' and the brass W is set on the level surface of 95 the plate F^x, with the end resting against the cross-head B, after which the clamp-screw is turned down upon the brass. The cutter is then fed forward by means of the screw I with a slow even movement until the cutting-edge 100 has passed across the face of the brass. In this manner the piece can be operated on sev-

eral times until the desired quantity of metal is removed.

Having thus fully described my invention, what I claim, and desire to secure by Letters 5 Patent, is—

1. The machine for reducing journal-brasses herein described, consisting of a suitable bed having at one end a cross-head B and a supporting-standard B' for a clamp-screw and at 10 the other end a post A' for a feed-screw I, a sliding plate E, having a planer-iron F and a plate F^X to hold the brass to the cutting-edge of the planer, and the adjustable arm C and clamp-screw D, combined for operation 15 as set forth.

2. In a machine for reducing brasses, the combination, with the stationary bed having a cross-head and means for holding the brass against vertical movement at the cross-head, of the sliding plate E, having interchangeable 20 planer-irons F F^X with beveled edges, and a feed-screw to move said plate, substantially as described.

In testimony that I claim the foregoing I have hereunto set my hand and seal.

EDWARD FERRISS. [L. S.]
